EVERETT R. MANLEY, OF FAIRMONT, WEST VIRGINIA

ADJUSTABLE ROTARY PRESSING MACHINE

Application filed May 10, 1927. Serial No. 190,217.

My invention relates generally to pressing machines, and more particularly to the hot or cold pressing of electric coils, as motor and armature coils, and to the hot or cold 5 pressing of such forms as mica insulating tubes and the like.

In my device a new method is employed in the process of hot or cold pressing of armature coils, and it differs from the old 10 method in that a square or multisided rotor is used, each side of which is a working face for the pressing of the coils, thereby affording a continuous pressing cycle of operation in one press, and a considerable saving 15 of time and movement of the operator. In the presses in present use there is one stationary working face for the pressing operation embodied in one machine, making it necessary to employ a series of machines 20 to allow for the proper heating interval of time between the insertion and removal of the coil without suspending operation.

Furthermore, better results are produced 25 than those in presses now in use owing to the fact that facilities are afforded for the proper adjustment of the parts pressing the coil thus permitting the pressing of a coil to any desired size of cross section.

Furthermore, in my invention, the construction and arrangement of the various 30 parts for the pressing operation are such that there are no loose parts that need removal during the entire cycle of operation. Presses in present use have loose parts that 35 have to be removed at some time during the cycle of operation. The removal of these loose parts causes extra labor and a loss of time, and does not give a machine that is compact and self contained.

Furthermore, my invention provides 40 adjustable and movable means of pressing armature and motor coils of various shapes and sizes. Armature and motor coils in most cases are of such shape that the ends 45 are offset from that part of the coil that needs pressing. My machine is so constructed and its parts so arranged as to readily press coils of practically any shape or size.

Furthermore, my invention is readily and 50 conveniently adaptable to the use of gas,

steam, hot water, or electric heating for hot pressing, and for cold pressing is adaptable to the use of cold water or cold air.

In the accompanying drawings, forming a part of this specification, and in which 55 similar characters of reference indicate like parts throughout the several views, Fig. 1 is a vertical side elevation showing one face of the rotor. It may be stated that each 60 face of the rotor is identical in every detail for the pressing of the coils. Fig. 2 is a vertical section thru the rotor on line 2—2 of Fig. 1. Fig. 3 is a vertical section thru the rotor on line 3—3 of Fig. 1, and with 65 parts removed from two working faces, and with center shaft removed. Fig. 4 is a section on the line 4—4 of Fig. 1, showing the top pressing yoke in relation to the lifting springs, and the method of holding the side 70 pressing bar to the side bar holder. Fig. 5 is a section on the line 5—5 of Fig. 1, showing 75 the adjusting screw for regulating the downward movement of the top pressing yoke.

The half bearings 1, the legs 2, and base 75 board 3, constitute the supporting frame of the machine. The rotor 4 is mounted upon the shaft 5 and held rigidly to shaft by the set screw 6. The shaft 5, with the rotor 4, 80 is free to revolve in the bearings 1. Longitudinal movement is prevented by the collars 7 upon the shaft.

The rotor 4, as shown, has four working 85 faces and may have more or less, but preferably four. (See Figs. 1, 2, and 3.) Each working face for pressing the coil or object has identically the same equipment upon it. The top pressing yoke 8 fits over a lug 9 of rotor 4. The screw 10, operated by lever 11, passes thru a hole in yoke 8, and screws 90 into the lug 9 of rotor 4. Turning the lever 11 moves the yoke 8 up or down. Springs 12, fitting in lug 9, and pressing against the underside of yoke 8, keeps the yoke 8 firmly 95 against the head of screw 10 in all positions of the yoke. (See Figs. 1 and 4.) Adjusting screws 13 limit the downward movement of the yoke 8. The side pressing bar 14, producing the side press against the coil or 100 form to be pressed, is held to the side bar

holder 15 by means of screws 16. The screws 16 are threaded into the holder 15, and have round turned ends that fit into a longitudinal groove 17 in the side bar 14. The side bar may thus be moved in a longitudinal direction or removed and another one readily put in its place. (See Figs. 1 and 3.)

The side bar holder is actuated back and forth by means of the screw 18, to which is rigidly attached a wheel 19 with a handle 20. The screw 18 is screwed into the fulcrum block 21, which fits into a longitudinal recess in rotor 4, and may be moved longitudinally across the face of the rotor. The side pressing bar 14 may thus be moved parallel to the top pressing yoke the entire length of the working face of the rotor. This feature of my invention particularly facilitates the pressing of motor and armature coils of such design that the offset part of the coil must be free from interference during the pressing operation. When such a coil is placed in the press with the offset endlapping over the end of the rotor, the fulcrum block 21 may be moved to any position necessary to apply the side pressing bar 14 to the center of the coil, thereby giving a uniform pressure to the coil. The fulcrum block 21, is held to the rotor 4 by two bolts 22, which pass thru the elongated slot 23. A plate 24 acts as a washer. (See Figs. 1 and 3.) The screw 18 has a turned down end with a circular groove 25 cut into it and fits into a hole in the side bar holder. A screw 26, in side bar holder 15, has a turned down end to fit into this circular groove in the end of screw 18, thus holding the side bar holder securely to the screw 18. A shoulder 27, on screw 18, takes the thrust incident to the pressing operation of the side pressing bar 14. This thrust is taken thru the screw to the fulcrum block 21, and thence to the recess in the rotor 4. (See Fig. 3.)

The coil to be pressed is placed on the rotor at 28. It will be observed from Fig. 3 that the side pressing bar 14 is so designed, that, in conjunction with yoke 8, the final size of the coil is determined. This is affected by the yoke and side bar taking contact at point 29, when the coil is pressed to its final size. Various cross sectional sizes of coils may be made by the use of side bars of suitable dimensions at point 28.

Or the size of coil to be pressed may be determined as shown by Figs. 4 and 5. The side bar 14 is designed so as not to make any contact at point 29, as shown in Fig. 4, but the downward movement of yoke 8 is limited by setting the adjusting screws 13, Figs. 1 and 5, so as to give the required size of coil in space 28.

The heating of the rotor may be done by any well known method but for convenience the drawings show the application for heating by gas, which is the method most com-

monly used. The valve 30 has a stem 31, which fits into a hole 32 in shaft 5, and a swivel joint is provided by means of a packing gland 33, which permits the valve to remain stationary when the rotor is revolved. The hole 32 extends to a point where the four pipes 34 are attached to the shaft. Near the rotor a burner 35 is provided to regulate the mixture of air and gas. The noses of the burners fit into pipes 36, which are fitted into holes in the end arms of the rotor. The opposite ends of the pipes 36 are capped. The pipes 36 have perforations to emit the gas and provide the flame for heating. It will be noticed that the pipes 36 are placed so that the flame will give the greatest heat to that part of the rotor immediately underneath the place 28, where the coil will be inserted for pressing. (See Fig. 3.) As stated before any method of heating may be employed such as gas, hot water, steam, or electricity. The openings 37 in the rotor are for the application of hot water, steam, or electricity. Electric coils may be inserted in the openings 37, or the openings may be used as part of the circuit for hot water or steam. In any case suitable attachments and fittings may readily be used for such heating methods. In the case of a cold press the openings 37 will be in the circuit of cold water or cold air, and suitable attachments and fittings will be employed.

The operation of my invention for hot pressing will now be explained. The yoke 8, and the side pressing bar 14, are withdrawn from the position shown in Figs. 3 and 4, by means of lever 11 and wheel 19 respectively. The coil is placed in space 28, and then the yoke 8 is screwed down, and side bar 14 screwed forward to press against the coil. The rotor is then turned around to the next working face and another coil is inserted. This process continues until the first coil inserted comes back to its initial position and a final tightening of the yoke 8 and side bar 14 is made. This final tightening may be made at any stage of the revolution of the rotor. The coil is then removed by releasing the yoke 8, and side bar 14, and transferred to an adjacent cold press, and another coil is put in the rotor. The rotor is revolved and the oncoming coil removed to the cold press and so on the process indefinitely continues.

I am aware that prior to my invention, hot pressing machines have been made consisting of one working face and for the application of heat in various forms. I therefore do not claim such a combination broadly; but

I claim:

1. In a molding machine having on its face thereof an adjustable yoke which is normally held away from said face which carries it, an adjustable side bar having a

notch therein which limits the adjustment of the yoke towards the working face of the molding machine.

2. In a molding machine having on its face thereof an adjustable yoke which is normally held away from said face, an adjustable side bar having a notch therein which limits the adjustment of the yoke towards the face of the molding machine, the working face of the machine, yoke and side bar, defining a mold cavity.

3. In a molding machine having a plane surface on which at right angles projects a lug, said lug having thereon an adjustable yoke which is adjustable in parallelism with said lug, and a side bar adjustable parallel with the plane surface of the molding machine, the lug, yoke, side bar, and the plane surface of the machine defining the mold cavity.

4. In a molding machine for molding objects of quadrilateral cross section, whose mold cavity is formed by two plane stationary members at right angles to each other and by two movable mold members which form the other sides of the mold cavity, one of said movable mold defining members limiting the movement of the other movable mold defining member along the side of the stationary mold member.

Signed at Fairmont, West Virginia, this ninth day of May, nineteen hundred and twenty seven.

EVERETT R. MANLEY.
